BATTERY OPERATED TOOTHBRUSH, CHARGER AND HOLDER COMBINATION

Raymond T. Cassidy, Stratford, and John F. Daniels,
Bridgeport, Conn., assignors to Sperry Rand Corpora-
tion, New York, N.Y., a corporation of Delaware

Filed Oct. 2, 1962, Ser. No. 71,957

Term of patent 14 years

(Cl. D9—2)

FIG. 1

FIG. 2

FIG. 3

Des. 197,208

PAGE 2

FIG. 4

FIG.5

FIG.6

FIG. 1 is a front elevational view of a battery operated toothbrush, charger and holder combination embodying our new design;

FIG. 2 is a perspective view of the charger and holder portions;

FIG. 3 is a perspective view of the battery operated toothbrush of FIG. 1, showing the left side, front and top thereof;

FIG. 4 is a perspective view of the battery operated toothbrush of FIG. 3 in inverted position showing the left side, rear and top thereof;

FIG. 5 is a perspective view of the battery operated toothbrush of FIG. 1 showing the right side, bottom and rear thereof; and

FIG. 6 is a perspective view of the rear of the charger and holder portions showing the bottom and the side opposite to the side shown in FIG. 2.

The essential features of the design reside in the portions shown in solid lines on the drawings.

We claim:

The ornamental design for a battery operated toothbrush, charger and holder combination, substantially as shown and described.
